(57) **CLAIM**

The ornamental design for a washing station, as shown and described.

DESCRIPTION

FIG. 1 is a left perspective view of a washing station, showing our new design.

FIG. 2 is a right perspective view thereof.

FIG. 3 is a front view thereof.

FIG. 4 is a back view thereof.

FIG. 5 is a right side view thereof.

FIG. 6 is a left side view thereof.

FIG. 7 is a top view thereof.

FIG. 8 is a bottom view thereof.

FIG. 9 is a cross-sectional bottom view taken from where the faucet meets the countertop.

FIG. 10 is a left perspective view with the privacy shroud removed.

FIG. 11 is a right perspective view with the privacy shroud removed.

FIG. 12 is a left side view with the privacy shroud removed.

FIG. 13 is a right side view with the privacy shroud removed; and,

FIG. 14 is a top view with the privacy shroud removed.

The broken lines are directed to environment, for illustrative purposes only, and form no part of the claimed design.
